ATTACHMENT FOR REFRIGERATING SYSTEMS

Edgar T. Link, Allentown, Pa.

Application September 13, 1934, Serial No. 743,921

4 Claims. (Cl. 62—1)

This invention relates to an attachment for a refrigerating system, the general object of the invention being to provide means whereby the system can be easily serviced, and voided, with 5 means for automatically voiding the system in case of fire.

This invention also consists in certain other features of construction and in the combination and arrangement of several parts, to be hereinafter fully described, illustrated in the accompanying drawings and specifically pointed out in the appended claims.

In describing the invention in detail, reference will be had to the accompanying drawings 15 wherein like characters denote like or corresponding parts throughout the several views, and in which:

- Fig. 1 is an elevation of the device.
- Fig. 2 is a vertical sectional view thereof.
- Fig. 3 is a section on line 3—3 of Fig. 2.
- Fig. 4 is a section on line 4—4 of Fig. 2.
- Fig. 5 is a view of the lower part of the pointed stem.
- Fig. 6 is a view of the split ring for holding a filter screen in position.
- Fig. 7 is a view of the screen.
- Fig. 8 is a view of another part of the valve assembly.

In these drawings, the numeral 1 indicates the body of the device which has a plug 2 closing its upper end, the plug being provided with a threaded hole 3 for receiving a line leading from the system. The upper part of the body forms a chamber 4 which contains the refrigerant drying material 5, such as anhydrous calcium chloride. This material rests on a filter or screen disk 6 which in turn rests on a split ring 7 seated on a shoulder 8 formed at the bottom of the chamber, said bottom having a recess 9 therein of smaller diameter than the chamber so as to provide the shoulder and this recess and the disk seated on the ring forms a space below the material 5. A smaller chamber 10 is formed in the lower part of the body and is separated from the first chamber by a partition forming part 11 of the body which is provided with a centrally arranged passage 12 connecting the two chambers together. A tubular stem 13 has its upper end threaded in the lower end of the passage 12 and the bore of the stem forms a continuation of the passage 12 with the lower end of the stem spaced a considerable distance from the bottom of the chamber 10. Flanges 14 are formed on the stem and act as stops for a float disk 15 which is preferably white so that it will readily be distinguished from

the refrigerant and oil entering the chamber 10. A glass cylinder 16 is placed in the chamber 10 and has its upper end bearing against a gasket 17 and a washer 18 closes the lower end of cylinder. The lower end of the body 1 is provided with an opening for permitting access to the parts within the chamber 10 and this opening is closed by a threaded plug 19. The wall of the chamber 10 is formed with a window 20 covered by a part of the glass cylinder so that the stem 10 and the float and a portion of the interior of the chamber can be seen. The lower part of the body is of less diameter than the upper portion and an intermediate part is threaded as at 21 for receiving the threaded upper end of a cap or 15 cover 22 which covers the window and prevents the glass cylinder from being broken so the cover can easily be removed when the parts are to be observed through the window.

An outlet passage 23 extends from the top of 20 the chamber 10 through a side portion of the part 11, the outer end of the passage being enlarged and threaded to receive the threaded end of a valve casing 24. This casing is adapted to be connected in any suitable manner to the evaporator by its threaded outer end 25 and a valve 26 controls the bore of the casing, said valve having its stem 27 passing through a gland 28 and having a wrench engaging part 29 at its outer end. A tube 30 is connected with the valve casing and 30 a cap 31 connects the outer end of the tube with a pipe 33 and a disk 34 of fusible material normally closes communication between the tube 30 and the pipe 33 and if a fire occurs, this disk will melt and thus the refrigerating system will 35 be drained.

A stem 35 slidingly passes through the stem 27 and has a handle 36 threaded to its upper end and a threaded intermediate part of the stem 35 is threaded in a socket formed in the lower end of 40 the valve 28, as shown at 37, and the stem 35 carries a collar 38 having a gasket thereon for forming a fluid tight connection with the lower end of the valve when the parts are in the position shown in Figure 2. The lower end of the stem 35 45 is pointed so that by unscrewing the stem 35 from the valve 28 and pressing upon the stem 35 it can be forced downwardly to cause its pointed end to puncture the disk 34 so that the system can be drained and by connecting the pipe 33 to a source 50 of supply the system can be charged or this pipe 33 can be used for bypassing the fluid from one part of the system to another part. By lowering the valve 28 upon the seat formed at the upper 55

end of the tube 30 the pipe 33 can be disconnected from the rest of the system.

As will be seen, the refrigerant fluid entering the device must first pass through the material 5 in the chamber 4 which will remove moisture and then pass through the filter 6 which removes dirt and then the fluid enters the passage 12 and flows through the stem into the chamber 10. As it passes from the stem, it strikes the reflector 18' carried by the washer 18 and then the fluid passes upwardly filling the cylinder and finally passes through the passage 23 through the valve casing 24 to the evaporator. Any dirt passing the filter will drop by gravity onto the reflector 18' and the fluid will wash this dirt from the reflector into the bottom of the chamber 10 where it can be removed whenever desired. The fluid in the chamber 10 will of course act on the float 15 so that one can see whether or not the chamber is full, empty or partly full by observing the float through the window 20 after removing the cover 22. This provides means whereby the operator servicing the system can readily tell when the tubing or lines to which the device is attached are empty without opening any valves or the like, thereby eliminating danger of odors from the escaping fluid and loss of fluid. By making the stem 13 of material that will corrode, the corrosion of this stem will indicate that the fluid contains moisture and thus the drying material is not functioning properly. By raising the compressor at one end, the amount of liquid in the receiver or condenser can be ascertained by looking through the window 20.

35 This invention aids the service-man to service the job by sight instead of by guess work and by the use of gauges and eliminates disagreeable odors, loss of fluid and other objectionable features of servicing a refrigerating system in the usual way. The device also shows the service-man by sight whether dirt and moisture are collecting in the system and the proper amount of oil and fluid is flowing through. The attachment can be located wherever desired in the system.

40 45 It is thought from the foregoing description that the advantages and novel features of the invention will be readily apparent.

It is to be understood that changes may be made in the construction and in the combination and arrangement of the several parts, provided that such changes fall within the scope of the appended claims.

I claim:

1. An attachment for a refrigerating system comprising a body having upper and lower chambers therein and a passage connecting the chambers together, that part of the body containing the lower chamber having a window therein, the upper chamber receiving the fluid from the system, a stem located in the lower chamber and having its upper end in communication with the

passage, a float carried by the stem, a glass cylinder in the lower chamber, said stem having its lower end terminating an appreciable distance above the lower end of the lower chamber and discharge means connected with the top of the 5 lower chamber.

2. An attachment of the class described comprising a body having upper and lower chambers therein and a passage connecting the chambers together, the top of the upper chamber having an 10 inlet, the lower part of the body having a window therein for communication with the lower chamber, a glass cylinder in the lower chamber covering the window, a stem having its upper end in communication with the passage and its lower 15 end spaced an appreciable distance from the lower end of the lower chamber, a float carried by the stem, means carried by the stem for limiting upward and downward movement of the float, a reflector in the bottom of the lower chamber 20 located under the stem, discharge means connected with the top of the lower chamber, and a detachable cap connected with the lower part of the body and covering the window.

3. An attachment of the class described comprising a body having upper and lower chambers therein and a passage connecting the chambers together, the top of the upper chamber having an inlet, the lower part of the body having a window therein for communication with the lower 30 chamber, a glass cylinder in the lower chamber covering the window, a stem having its upper end in communication with the passage and its lower end spaced an appreciable distance from the lower end of the lower chamber, a float carried by the 35 stem, means carried by the stem for limiting upward and downward movement of the float, a reflector in the bottom of the lower chamber located under the stem, discharge means connected with the top of the lower chamber, a detachable cap 40 connected with the lower part of the body and covering the window, said discharge means including a valve casing, a manually operated valve for said casing, a tube carried by the casing, a pipe connected with the tube a removable fusible 45 disk separating the tube from the pipe, and manually operated means for puncturing the disk.

4. An attachment for a refrigerating system comprising a body having upper and lower chambers therein, the upper chamber having an inlet, and an outlet for the top of the lower chamber, a conduit connecting the two chambers together, said conduit including a stem extending into the lower chamber and formed of corrosive material, 55 a float carried by the stem, the walls of the lower chamber having a window therein, a transparent member in the lower chamber extending across the window and a removable cap for closing the window.

EDGAR T. LINK. 60
